CLAIM

I claim the ornamental design for a pan with one handled hand grip, as shown and described.

DESCRIPTION

FIG. 1 is a perspective view of the pan with one handled hand grip.

FIG. 2 is a left side elevation view.

FIG. 3 is a right side elevation view.

FIG. 4 is a front elevation view.

FIG. 5 is a rear elevation view.

FIG. 6 is a top plan view; and,

FIG. 7 is a bottom plan view of the pan with one handled hand grip.
